HANGER CATCH FOR TOOLS AND OTHER
OBJECTS

Harold Tinsley Caldwell, Claremont, Calif.

Application August 12, 1939, Serial No. 289,922

6 Claims. (Cl. 145—35)

My invention relates to a hanger catch for tools or other objects, and particularly to a hanger catch capable of being secured to and made a permanent part of the tool and adapted to function as a means of engagement with a vertical or inclined surface of an object in a manner to support the tool thereon.

My invention is particularly adapted for use with carpenters' saws and other tools and the tools of artisans engaged in construction or repair work. Such tools are commonly leaned against the inclined or vertical surface of a wall, sawhorse, or other object, in which case they frequently fall with possible injury to the tool and inconvenience to the artisan. In some cases, such as, for instance, when artisans are working upon a sloping roof, it is difficult and inconvenient to provide means for supporting a tool laid down upon the roof. A tool provided with a hanger catch made in accordance with my invention will be automatically secured in supported relationship to a wall, sawhorse, or roof having a vertical or inclined surface. Tools provided with a hanger catch of my invention may be laid down and picked up frequently without attention upon the part of the artisan to the matter of support for the tool, and without danger of the tool falling from or slipping upon the surface on which it is laid.

It is one object of my invention to provide a device to be mounted upon a tool or other object which, when the tool is placed against a vertical or inclined surface, will automatically engage the surface and support the tool.

It is another object of my invention to provide such a device which will automatically assume an inoperative and harmless position when the tool is removed from the supporting surface, and in which it will be protected from damage and will not cause injury to the artisan or to surrounding objects.

It is another object of my invention to accomplish the aforesaid objects by a simple and inexpensive device which is unlikely to become broken or need repairs or adjustment.

Other objects of the invention and advantages attendant upon its use will appear from the following description of the invention, the drawing, and the appended claims.

In the drawing:

Fig. 1 is a plan view of a hanger catch embodying my invention;

Fig. 2 is a side elevation thereof;

Fig. 3 is a vertical sectional view taken along the line 3—3 of Figs. 1 and 2;

Fig. 4 is a sectional view of the catch taken on the same plane as that of Fig. 3, showing the catch mounted in a saw handle and in a position of engagement with an inclined piece of wood;

5 Fig. 5 is a side elevation of a saw equipped with a hanger catch of my invention.

My invention is shown and described herein as embodied in a hanger catch for a saw, but it is to be understood that this is for illustrative purposes only and that the invention is capable of use on other tools and objects.

A housing 2 in the general form of a cylindrical cup is formed with an integral threaded shank 17 which engages an interiorly threaded screw 1, which is one of several similar screws such as are commonly provided on saw handles to secure the saw blade in position.

The side of the saw handle opposite the screw 1 is formed with a cylindrical recess 19 to receive 20 the housing 2. The housing is prevented from turning in the recess 19 by means of a laterally projecting rib 11 which seats in a correspondingly shaped slot in the wall of the cylindrical recess 19 of the handle.

25 An arm 4 is revolvably mounted upon a horizontal pin 5 which is secured to and between opposite sides of the wall 21 of the housing 2. The arm 4 is thus adapted to oscillate over a limited range of angular movement. A needle 7 is seated

30 in the body of the arm 4 and rigidly held in position therein by a set screw 8 with a pointed end 22 of the needle projecting from one end of the arm 4. The pointed end 22 of the needle 7 fits within and is shrouded by a notch 14 formed in 35 the side wall of the housing 2 and an aligned notch 15 in the saw handle 3 and is held in seated and shrouded position in those notches by a spring 6 held between the bottom wall 23 of the inner chamber of the housing 2 and the 40 under surface 24 of the arm 4.

A safety catch 10 is mounted upon a vertical rivet 9 carried by the housing in a manner to permit it to be swung into or out of engagement with a notch 12 formed in the rear face of the 45 arm 4, or into a notch 16 also formed in the rear face of the arm 4 and near the upper edge thereof. The notches 12 and 16 are so disposed in the arm 4 that when the notch 12 is engaged by the catch 10, the needle 7 is held immovably in its shrouded position in the notches 14 and 15, and when the notch 16 is engaged by the catch 10, the needle 7 is held in its uppermost position against the action of the spring 6 and projects outwardly in an unshrouded position from the body of the 50 saw handle, as shown in Fig. 4.

It will be understood that while I have described my hanger catch in connection with and as mounted on a saw handle, the device readily lends itself to manufacture as a separate article of commerce to be sold for installation on saw handles or, with appropriate modifications as to the shape of the housing and means of attachment, on other tools and other objects.

When installed upon a saw handle or other tool, the device operates as follows:

The catch 10 is placed in a position in which it is out of engagement with both notches 12 and 16. The spring 6 holds the needle 7 in retracted position in the notches 14 and 15. When the workman wishes to lay aside the saw temporarily, he presses it against the side of a vertical or nearly vertical surface of an article of wood or other material capable of being pierced by a needle point, or he lays it down without the manual application of pressure upon an inclined surface 25 of a similar article of wood 26 of a wall constructed of boards of wood or like material. In either case the outer portion of the arm 4 will be contacted by the surface of the object against which the saw is placed, compressing the spring 6 and causing the point 22 of the needle 7 to move outwardly into a position of angular relationship with the longitudinal lines of the saw. In this position the force applied to the needle by the manual pressure of the workmen or by the weight of the saw as the case may be will cause the needle point to pierce and the needle will enter the surface of wood or other like material and then support the saw against the action of gravity.

When it is again desired to use the saw, it is lifted, disengaging the point of the needle 7 from the retaining object and permitting the spring 6 to retract the needle to its inoperative shrouded position within the notches 14 and 15.

If it is desired to hang the saw or other tool from a horizontal surface, such as a desk, the workman may press upon the arm 4, moving the needle 7 into its projecting unshrouded position to enable it to engage and rest upon the horizontal surface.

When the saw is not being used for any extended period of time, the needle point may be secured in its retracted shrouded position by placing the catch in the notch 12, preventing accidental exposure of the needle point to the possible harm of persons or objects.

When, on the other hand, for any reason it is desired to lock the needle in operative unshrouded position, as, for instance, to insure its ready engagement with a wooden object without the aid of the application of pressure by the workman, or to enable it to engage and rest upon a horizontal surface, the catch 10 may be swung into position in the notch 16, preventing the spring 6 from retracting the needle 7.

The only part of the device of my invention which is subject to any considerable wear is the needle 7, which is readily removable for replacement by a new needle by simply loosening the set screw 8.

While in the embodiment of my invention described herein and shown in the drawing there is used a needle having a sharp point, it is apparent that a projection having a blunt outer end may be used with vertical or inclined surfaces which have horizontal ribs or other horizontally faced projections capable of supporting engagement with a projection of such character.

It is also obvious that while in the embodiment

of the invention shown herein the arm 4 is movable and the housing upon which it is pivoted is stationary with respect to the saw handle, it is within the scope of my invention to stationarily mount the catch in a position projecting from the surface of the saw handle and provide it with a movable, resiliently mounted shield, guard, or hood which will yield inwardly toward the handle face, when the saw handle is brought in contact with a vertical or inclined surface, exposing the catch for engagement with the supporting object. My invention may be used in other modified forms adapted to various tools and objects and is not limited to the particular embodiment shown but is defined in the appended claims.

I claim as my invention:

1. In combination with a tool having a recess formed therein: a lever intermediately pivoted within said recess on an axis substantially parallel to the surface of the tool adjacent said recess and oscillatable over a limited angle of movement; a catch projection on one end of said lever adapted at one limit of said movement to engage an external object in a manner to support said tool and at the other limit of said movement to be precluded from said engagement; a lug on the other end of said lever disposed thereon to assume a position for pressural engagement with said object when said lever is in said second position; and spring means for urging said lever to its second position.

2. In combination with a tool: a tool supporting element movably mounted on the tool; means on the tool for stopping the movement of said element at a first projecting position for tool supporting engagement with an external object and at a second withdrawn position precluding such engagement; resilient means for urging the element from its first to its second position; means operatively connected to the element for moving the element from its second to its first position, comprising a projecting lug disposed for pressural engagement with said object and operable by said engagement to move inwardly toward said tool; and means for positively locking the element in its second position against the action of said moving means.

3. In combination with a tool: a tool supporting element movably mounted on the tool; means on the tool for stopping the movement of said element at a first projecting position for tool supporting engagement with an external object and at a second withdrawn position precluding such engagement; resilient means for urging the element from its first to its second position; means operatively connected to the element for moving the element from its second to its first position, comprising a projecting lug disposed for pressural engagement with said object and operable by said engagement to move inwardly toward said tool; means for positively locking the element in its second position against the action of said moving means; and means for positively locking the element in its first position against the action of said resilient means.

4. In combination with a hand saw or other like tool: an element movably mounted on the tool and movable between a first projecting position in which it is capable of having contact with a surface of a wall, floor, roof or other like external object, said contact being of a character to hang the tool on said object and a second withdrawn and shrouded position in which it is precluded from having such contact; and an in-

wardly yieldable projecting means carried by said tool operable by a pressural engagement with said surface of said object to move inwardly toward said tool for moving said element from its second position to its first position.

5. In combination with a hand saw or other like tool: an element movably mounted on the tool; means on the tool for stopping the movement of said element at a first projecting position in which it is capable of having contact with a surface of a wall, floor, roof or other like external object, said contact being of a character to hang the tool on said object and at a second withdrawn position precluding such contact; resilient means for urging the element from its first position to its second position; and means operatively connected to the element for moving the element from its second position to its first position, comprising a projecting lug disposed

for pressural engagement with said surface of said object and operable by said engagement to move inwardly toward said tool.

6. In combination with a hand saw or other like tool: an element mounted on and projecting from the tool in a position in which it is capable of having contact with a surface of a wall, floor, roof or like external object, said contact being of a character to hang the tool on said object; 10 means on the tool for shrouding said projecting element to render it incapable of having such contact; and inwardly yieldable movable means carried by said tool comprising a projecting lug disposed for pressural engagement with said surface of said object and operable by said engagement to move inwardly toward said tool for relatively moving said element and said shrouding means to unshroud said element.
